UNITED STATES PATENT OFFICE.

HEINRICH SCHNEIDER, OF LENZBURG, SWITZERLAND.

SPINNING-MACHINE GUIDE.

Application filed July 30, 1924, Serial No. 729,129, and in Germany February 5, 1924.

This invention relates to improvements in and appertaining to spinning, twisting and like machines for the production of yarns, rove and threads and more particularly to the type known as flyers or roving frames and having two staggered series of bobbins or spindles for the production of roving.

For the production of rove flyer frames have hitherto been used, the bobbins of which possess a special drive. Self-braking bobbins of the usual construction cannot be employed here, as the rove with its soft twist is not able to transmit the pull necessary to overcome the normal bobbin friction. The speed of the flyer and of the bobbin must furthermore have a certain ratio for each layer of yarn upon the bobbin and to effect this the flyer and bobbin drive have been coupled with each other by a gear (differential) drive. Under those circumstances the common drive of all the flyers on the one hand and all the bobbins on the other hand through a differential gear from a common motor was the given solution of the problem.

Owing to the incident great number of gear wheels, worms and worm wheels such a machine operates, however, with a considerable noise and the individual parts are subject to an excessive wear and tear. These intermediate mechanisms also limit the speed of the flyer, so that the capacity of the frame cannot be raised beyond a certain maximum fixed by the maximum speed of the gear driven flyers. If a greater twist of the roving is to be attained, it is even necessary to reduce the output of the machine by reducing the speed of the delivery rollers.

In ordinary flyer spinning frames for spinning yarns with full twist, success has already been attained by driving each flyer individually and in the simplest manner by an electric motor, thereby increasing the speed of the flyers and thus the production of the machine. A further increase in the output of the frame results from the fact that on rupture of the thread only the individual flyer concerned need be stopped by switching off its motor, while the other flyers continue their work undisturbed. In this system self-braking bobbins are used, so that all driving parts for the bobbin are eliminated.

It has been found that rove cannot be spun on such frames principally owing to the following reasons. The angular devi-

ation at which the rove enters the hollow shaft of the flyer prevents the continuation of the twist up to the delivery rolls, owing to the tension to which the rove is now subjected, and the untwisted rove is liable to break; moreover, even if the rove be twisted it is still not sufficiently strong to turn an ordinary self-braking bobbin with certainty and breakage of the rove would occur. Again when the flyers are driven individually it is essential to maintain, particularly during starting and stopping, a reasonable ratio between the speed of the delivery rollers and flyers as otherwise the rove is liable to be broken or overtwisted.

According to my invention I provide a machine whereby the production of rove by means of flyer frames, and more particularly by means of frames with two series of staggered bobbins, is rendered possible and with this object in view my invention consists in the provision of a machine characterized by the feature that the flyers are individually driven by electric-motors in known manner, that guide members are provided between the supply rollers and the hollow shaft of the motor adapted to introduce the thread substantially vertically into the motor and that the bobbins are furnished with a known drag device the resistance against rotation of which is reduced as far as possible by special means.

By my invention I am able to produce cone shaped bobbins of rove, similar to the well known yarn cops.

An embodiment of my invention is illustrated in the drawing affixed to this specification and forming part thereof. These drawings represent in:

Fig. 1 a sectional view of the improved form of rove guide.

Fig. 2 a similar view illustrating an alternative form of guide and also means for taking up broken sliver.

Figs. 3, 4, 5 and 6 detail views illustrating suitable sections of the guide shown in Fig. 1.

Similar parts are indicated by similar reference numerals in the several figures of the drawings.

Referring to Figs. 1 and 2 the path of the rove from the delivery roller to the bore of the motor is diagrammatically shown by way of example. In these figures, 1 is the roller, 2 a pressure roller, 3 and 4 the upper ends of two motor bores, one of the rear and one of

the front series; 5 and 6 are guides and 7 and 8 designates the rove. From this drawing it is obvious, that this manner of guidance attains a vertical or at least substantially vertical entrance of the rove 7 and 8 into the bores 3 and 4 of the motors whereby the twist is continued right up to the delivery rollers. The groove provided in the guides 5 and 6 for the rove may have any suitable cross-section. A number of constructive possibilities are illustrated in Figures 3 to 6.

While in the construction according to Fig. 1 a continuous guidance of the rove along a curved line takes place, a polygon path is chosen instead in Fig. 2. The guidance is here effected by round rods 9. Here also the yarn enters the bore of the motor vertically or substantially vertically. As the rove makes contact at a few points only, friction on the guiding elements is reduced to a minimum.

While in flyer frames with mechanically driven flyers and bobbins it is necessary to stop the entire frame when a single rove breaks, whereby a considerable reduction of the output of the machine is caused, flyer frames having electrically individually driven flyers only require the stopping of the flyer belonging to the broken rove, by switching off its motor. As the operative is, however, not always able to re-tie the broken rove at once the delivery rollers continue to pay out the rove and the latter is heaped up on the spinning rail and may reach adjacent slivers and cause rupture of further threads. In order to prevent this a roller is disposed in front of the delivery roller, and this additional roller is preferably driven in the opposite direction, but at substantially equal circumferential speed. If a rove breaks the operative lays the rove which is still being delivered around this additional roller, while switching out the motor, which always can be effected without any considerable loss of time. The roller then winds up the broken end and thus prevents its interfering with adjacent rove. This additional roller is in Fig. 2 indicated by the reference number 10 and the course of the rove towards the roller after the rupture is indicat-

ed in broken lines. When tying up again for spinning, the rove is simply severed between the supplying roller 1 and the roller 10. While this roller 10 is shown only in Fig. 2, it is implied also in the arrangement shown in Fig. 1.

If the available space renders it possible, this roller may also be disposed below the course of the thread so that after rupture of a thread the loose end drops upon this roller by gravity and is wrapped around it automatically. In order to increase the adhesion of the broken end upon this roller, the latter is preferably covered with a suitable friction material, such as plush or the like.

It will be readily understood that I do not limit myself to the details of construction illustrated by way of example and that these may be modified in many ways without departing from the spirit of my invention.

What I claim as my invention and desire to secure by Letters Patent is:—

1. In a spinning frame having individually motor driven spindles, supply rollers, guide elements for the rove disposed between said supply rollers and the rove inlet into the spindles and adapted to introduce the rove into each spindle substantially in the direction of its rotation axis. 75

2. In a spinning frame having individually motor driven spindles, supply rollers, guide elements for the rove having substantially curved grooves and being disposed between said supply rollers and the rove inlet into the spindles and adapted to introduce the rove into each spindle substantially in the direction of its rotation axis. 80

3. In a spinning frame having individually motor driven spindles, supply rollers, guide elements for the rove disposed between said supply rollers and the rove inlet into the spindles and adapted to introduce the rove into each spindle substantially in the direction of its rotation axis and revolving pick-up rollers disposed at the delivery side of said supply rollers and adapted to take up broken ends of rove. 90

In testimony whereof I affix my signature.

HEINRICH SCHNEIDER.
